METHOD OF PRODUCING CATHODE SLEEVES FOR THERMIONIC VALVES

Henry Kershaw, Belleville, N. J.

Original application January 23, 1940, Serial No. 315,250. Divided and this application February 27, 1940, Serial No. 321,125

13 Claims. (Cl. 29—155.5)

My invention relates to a cathode sleeve for thermionic valves or vacuum tubes and to the method of producing the same.

In United States Patent 2,029,482 a cathode sleeve or cylinder is shown, formed from a strip of sheet metal, having its side edges interlocked, by providing oppositely facing bent tongues upon the strip. These interlocking edges provide a seam of four layers of metal, and the seam is continued beyond one end of the tube or cylinder to provide a tab, which is to be attached to a post. The tab is formed from spaced tab sections at one end of the sheet and each of these tab sections is folded upon itself to provide a continuation of the interlocking tongues. Considerable difficulty is experienced in producing this sleeve or cylinder with the tab, as shown in Patent 2,029,482, commercially, and the difficulty resides principally in the formation of the tab integral with the sleeve or cylinder. As a result of this, these sleeves or cylinders ordinarily are produced without the tabs which are separate from the sleeve or cylinder and are subsequently welded to the sleeve or cylinder. This welding in place 25 of the tab is a separate operation and increases the cost of production of the product.

It has also been proposed to form the cathode sleeve or cylinder from an integral drawn tube and to provide a separate tab, which is subsequently welded to the drawn tube. This construction is shown in Patent 2,079,057. The drawn tube is expensive.

In accordance with my method, I form a sleeve having generally radially extending flanges, and portions of these flanges contact but the flanges do not interlock, and these flanges are welded together. The sleeve may be accurately formed in the desired shape, such as circular, square, or other shape in cross-section, and the sleeve will not be distorted by the welding of the flanges. The welding of the flanges securely unite the side edges of the sleeve, and the welding may be effected rapidly and cheaply. This dispenses with the expensive practice of forming interlocking tongues upon the side edges of the sleeve. In the practice of my method, the tab is formed of tab sections which are preferably in effect continuations of the flanges. Each tab section is single-layer and portions of their faces contact but have no interlocking engagement and are secured together by welding. The difficulty experienced in shaping tab sections into interlocking tongues is therefore eliminated, and the tab may be readily produced integral with the sleeve or cylinder. I 55 may also bend over upon the sleeve or cylinder

the originally generally radial welded flanges, providing a rib or seam. A portion of the welded flange may be left raised, for providing a shoulder. While it is preferred to bend down the welded flanges, the sleeve may be used without doing this. A further advantage of my construction is that the rib or seam produced by the bent-over welded flanges comprises but two layers of metal, thus effecting the maximum uniform distribution of heat. A further advantage of my construction is that the seam or rib may be arranged wholly upon the exterior of the sleeve, thus permitting of the close arrangement between the electrical heating unit and the sleeve, without liability of these elements contacting and scraping off the insulation from the heating unit.

The present application is a continuation in part of my original application for Cathode sleeve for thermionic valves and method of producing the same, Serial No. 259,908, filed March 4, 1939, 20 and my application for Cathode sleeve for thermionic valves, Serial No. 281,984, filed June 29, 1939, and which is a division of application 259,908. The present application is also a division of application 315,250, filed Jan. 23, 1940 25 for Cathode sleeve for thermionic valves.

In the accompanying drawings forming a part of this application and in which like numerals are employed to designate like parts throughout the same,

30 Figure 15 is a perspective view of the sleeve, showing the welded flanges bent down upon the sleeve and slit to form a stop shoulder,

35 Figure 16 is a transverse section through the knock-down punch showing the formation of the stop shoulder, the section through the knock-down punch being taken on line 16—16 of Figure 17.

Figure 17 is a bottom plan view of the knock-down punch,

40 Figure 18 is a perspective view, in a vertical position of the completed cathode sleeve, and,

Figure 19 is a side elevation of the cathode sleeve shown in Figure 18, assembled with a grid and associated elements.

45 In Figures 15 and 18 I have shown a cathode sleeve 20, which is cylindrical for the purpose of illustration. The sleeve 20 has single-layer flanges 21 and 22, which overlap, are welded together and bent over or down upon the sleeve, providing a seam of two layers and which serves to stiffen the sleeve. Tab sections 23 and 24 are formed integral with the sleeve, are in alignment with the flanges 21 and 22 and form in effect continuations of the same. The tab sections are also welded together. The flanges and tab sections have no interlocking engagement and are secured together solely by welding. The flanges 21 and 22 are arranged upon the outer surface of the sleeve and are transversely slit at 25, affording an outwardly projecting stop shoulder 26, which is generally radial.

50 The cathode sleeve 20 is formed from sheet metal, such as nickel. This sheet metal is thin and ordinarily has a gauge of .0015" (1.5 thousandths of an inch), although the invention is not restricted to this precise gauge. The drawings show the cathode sleeve in a greatly enlarged diameter. As shown in Figure 13^a the internal diameter of the cathode sleeve is .040" (40 thousandths of an inch) and its external diameter is .043" (43 thousandths of an inch). The width of the flanges and tab sections is .020" (20 thousandths of an inch). These dimensions may vary somewhat either way. Cathode sleeves are made having an internal diameter as small as .020" (20 thousandths of an inch). The dimen-

sions given are the average dimensions and are recited to show the inherent difficulties encountered in making a cathode sleeve. My invention is not restricted to the precise dimensions given.

5 I will now proceed to explain the method employed in producing the cathode sleeve 20. In the production of this cathode sleeve I start with a thin metal ribbon, such as nickel, preferably having a gauge of .0015", although the gauge may vary somewhat. This metal ribbon is designated by the numeral 21, Figure 1, and is wound in a roll 28 upon a spool 29, and is unwound from this spool in a step-by-step manner. As the metal ribbon is unwound from the spool it is transversely flat.

10 The step-by-step feed of the metal ribbon may be effected by any suitable means, and I contemplate using a block 30 having a flat recess 31. Arranged above the block 30 is a top 32 rigidly secured thereto and this top has a vertical opening 33, to receive a friction pin 34, forced down by a spring 35. When the spring acts upon the friction pin 34 this friction pin engages the ribbon 21 and holds it to the block 30 so that the ribbon will move with the block when the block 25 moves forwardly. When the block moves rearwardly, the intermediate portion of the spring 35 is elevated, relieving the tension from the friction pin 34, and the block may then slide rearwardly with relation to the ribbon, which is then held 30 against rearward movement. The spring 35 is attached to the top 32 and any suitable means may be employed to operate the spring and any suitable means may be employed to reciprocate the block 30. The block 30 is moved forwardly 35 on each cycle of operation for a distance equal to the combined length of the completed sleeve and tab sections.

40 The lower block 30 carries a forming roller 36, having a concave periphery which is channeled 40 or V-shaped in cross-section and the roller 36 coacts with an upper forming roller 37, carried by the top 32. The roller 37 is convex and has a periphery which is V-shaped in cross-section, corresponding to the cavity of the roller 36 and 45 adapted to enter the same. The low point 38 of the roller 36 is to one side of the center 39 of this roller, providing a face 40 longer than the face 41. The high point 42 of the roller 37 is to one side of the center 39 providing a face 43 50 longer than the face 44. The upper roller 37 is provided adjacent to one end of this periphery with an annular groove 45, to receive an annular set of drawing studs 46, carried by the roller 36.

55 When the block 30 and associated elements are moved from the rear position, Figure 1, to the forward position, it will advance the ribbon 21, as explained. When the ribbon is thus advanced, the forward portion of the ribbon is clamped against rearward movement and the tension of 60 the spring 35 is released from the pin 34 and the block 30 and associated elements are then moved rearwardly and returned to the rear position. The block 30 and the forming rollers 36 and 37 then travel rearwardly with relation to 65 the then stationary ribbon 21, and the peripheries of the forming rollers 36 and 37 engaging with the ribbon 21 form or bend the same into a V-shape, as shown. In this V-shape one side 47 is wider than the other side 48. At the same 70 time, the drawing studs 46 produce a row of spaced raised portions 49 adjacent to one longitudinal edge of the ribbon. These raised portions or bumps 49 have their convex faces next to the upper face of the side 47, Figure 2. The 75

ribbon is formed or bent into the V-shape and the raised portions 49 are formed when the block 30 and associated elements move rearwardly with respect to the ribbon. When the block 30 and associated elements move forwardly, they feed the ribbon forwardly, and that portion which is V-shaped is rendered thereby stiff so that it is fed forwardly by a pushing action, while that portion of the ribbon at the rear of the block 10 is fed forwardly by a pulling action. If the forward portion of the ribbon were not stiffened by the V-shape, it would not be sufficiently stiff to be properly pushed forwardly.

When the V-shaped portion of the ribbon is pushed forwardly it is moved to a stamping position and is arranged within a V-shaped recess 50 of a stationary die 51, having a vertical opening 52, to receive a punch 53, carried by a vertically reciprocatory head 54. The numeral 55 designates a stripper, having an opening 56 to receive the punch 53 and a groove 53' to receive the raised portions 49 and move downwardly by springs 57. The stripper 55 has its lower face V-shaped to conform to the shape of the recess 50. When the 25 V-shaped portion of the ribbon 27 is moved into the recess 50, the head 54 is shifted downwardly and the stripper 55 moves downwardly and clamps the V-shaped portion of the ribbon within the recess 50, subsequent to which the punch 53 moves down below the stripper 55 and enters the opening 52 of the die and stamps out the opening 57. When the head 54 rises, the punch 53 moves upwardly with respect to the stripper 55 and the V-shaped portion of the ribbon will be separated 35 from the punch by the stripper. When the head 54 is in the uppermost position both the stripper and punch are spaced from the V-shaped portion of the ribbon. When the stripper 55 is clamping the V-shaped portion of the ribbon in the recess 40 50, the ribbon is held against rearward movement, and during this time the block 30 and associated elements are shifted rearwardly. The formation of the opening 57 provides the tab sections 23 and 24, arranged adjacent to the longitudinal edges of 45 the V-shaped portion of the ribbon and extending longitudinally of such V-shaped portion beyond one end of the same.

When the block 30 and associated elements are again moved forwardly this V-shaped portion of 50 the ribbon is advanced to the sleeve forming or bending position, and when the head 54 again moves downwardly, the cutter 58 is moved upwardly to sever the tab sections 23 and 24, at 59, whereby the leading V-shaped ribbon section is 55 separated from the ribbon. This section is used to form the sleeve and tab of the cathode sleeve. Particular attention is called to the fact that the raised portions 49 extend throughout the entire length of the V-shaped portion and the entire 60 length of the tab section 24. When the leading section is thus shifted to the bending position it is introduced into a V-shaped recess 60 of a vertically movable forming die 61, then in the lowered position. The forming die also has a 65 cylindrically curved recess 62, receiving the apex of the V-shaped section. The cylindrically curved recess 62 is preferably less than half of a cylinder whereby the sides 47 and 48 of the section, when further bent extend upwardly in a diverging relation. The center of the recess 62 is to one side of the longitudinal center 63 of the die 61. The 70 numeral 64 designates a horizontal mandrel or core which is cylindrically curved for coaction with the recess 62. The mandrel or core 64 is 75 cylindrical except for an upper flat face 65, as

shown. The mandrel 64 is concentric with respect to the recess 62. During the forming of the sleeve, with the V-shaped strip within the recess 60, the mandrel 64 is held stationary above the die 61 and the die is first raised sufficiently to clamp the V-shaped section between the mandrel and the die and the die is then stopped before the mandrel 64 has reached its lowermost position within the recess 62 and the die 61 is held stationary. A knock-down die 66 is now moved 10 downwardly into engagement with the top of the mandrel 64 and forces it to the lowermost position within the recess 62 and the mandrel 64 and the recess 62 now bend the section to provide a lower cylindrically curved portion 67 carrying the up-standing upwardly diverging sides 47 and 48. The side 47 extends above the side 48, by virtue of the off-center arrangement of the recess 62 and the mandrel 64 and the wider side 47 carries the raised portions 49. After this operation, the 20 knock-down die 66 is elevated and separated from the mandrel 64. Horizontal reciprocatory electrical resistance welding jaws 68 and 69 are moved inwardly and engage the upstanding sides 47 and 48 and complete the forming or bending of the 25 same about the mandrel 64 and form the flanges 21 and 22. These jaws 68 and 69 are insulated from parts 61 and 64. The welding jaw 68 moves inwardly beyond the center 70 of the mandrel 64 while the welding jaw 69 moves inwardly and 30 terminates short of this center, whereby the flanges 21 and 22 are arranged adjacent to one longitudinal edge of the flat face 65 of the mandrel 64. The welding jaws 68 and 69 have vertically inclined welding faces 71, which are preferably free from notches although notches may be used if desired. The welding jaws extend for the entire combined length of the sleeve and the tab sections. 35

As the welding jaws 68 and 69 move inwardly 40 they first bring the convex ends of the raised portions 49 of the flange 22 and tab section 24 into contact with the flange 21 and tab section 23, and since these raised portions are convex, the minimum area is afforded at the instant of contact 45 between the raised portions and the flange and tab section, thereby producing the maximum resistance at the points of contact. As soon as the jaws move inwardly sufficiently to effect the contact, as described, a welding current is supplied 50 to the welding jaws 68 and 69, and the raised portions 49 and the contacting portions of the flange and tab section are rendered plastic, and during this welding period the jaws 68 and 69 continue to move inwardly until the flanges and tab sections 55 are brought into firm contact and the raised portions or bumps are flattened out. The inward pressure of the welding jaws 68 and 69 follow through during the entire welding period so that there can be no flashing and the flanges and tab sections 60 are brought into firm contact after the raised portions are flattened, and the current is cut off when the jaws still exert the inward pressure. I use an alternating current of low voltage and high amperage. Satisfactory results are obtained 65 by using an alternating current having a voltage of approximately three (3) volts and an amperage of approximately 2,000 amperes. During the welding period, the current stays on for only a short time, and I have found that satisfactory 70 results are obtained by having the current turned on for one-half (½) cycle. The invention is not restricted to the precise voltage and amperage and time recited, as these may be varied. The welding jaws also weld the tab sections 23 and 24 75

together in the same manner as the sides 21 and 22. The tab sections 23 and 24 are in alignment with the flanges 21 and 22 and are disposed in the planes of the same. The flanges and tab sections are arranged exteriorly of the sleeve, are inclined and are generally radial with relation to the sleeve and are disposed upon one side of the center of the sleeve. The mandrel or core 64 extends for the entire length of the sleeve and tab 10 section.

During the welding operation the die 61 and the mandrel 64 remain stationary, and they remain stationary during the next step of bending down the welded flanges and tab sections. After 15 the jaws 68 and 69 are moved to the open position, the knock-down die 66 is again operated. This knock-down die 66 extends throughout the entire length of the sleeve and tab. The knock-down die has a cylindrically curved recess 72, 20 having its center in alignment with the center of the recess 62. The flanges 21 and 22 which are inclined are off-set with respect to the center of the sleeve and the center of the recess 72. It is thus apparent that when the knock-down die 66 25 again descends it will engage the welded flanges 21 and 22 and the tab sections 23 and 24 and bend them down over the flattened portion of the sleeve, and this bending down will occur throughout the entire length of the sleeve and the tab 30 except for a short portion which provides the up-standing stop shoulder 26. The shoulder 26 is provided by forming the knock-down die 66, Figure 16, with a transverse slot 73 having a width corresponding to the length of the shoulder 26. A supporting element or hook 74 extends 35 into the slot 73 and is adapted to engage behind the shoulder 26, to prevent the same being bent down. The hook 74 supports the shoulder 26 and the edges of the slot 73 serve to cut or shear the flanges 21 and 22 at the lines 25. The hook element never moves downwardly sufficiently to engage the mandrel or sleeve thereon but does move downwardly sufficiently to engage behind the shoulder 26. The hook may be operated by any 40 suitable means. I have shown a spring 75 to raise the hook and an adjustable screw 76 carried by the knock-down die 66 to depress the hook. When the die 66 is raised the space between the screw 76 and the hook 74 is such that 45 50 the face of the recess 72 of the die 66 will engage the sleeve upon the mandrel 64 before the hook 74 has moved downwardly to engage such sleeve.

After the bending down operation the knock-down die 66 is raised, the hook 74 rises and the forming die 61 is lowered and the mandrel 64 is moved horizontally through a stripper 77 which strips the completed sleeve from the mandrel. This completes the cycle of operation of the method. The various instrumentalities employed 55 60 in the practice of the method will be moved in properly timed order, and they may be moved manually or automatically.

The sleeve shown in Figure 18 is thereby produced, and the bent-down flanges 21 and 22 provide a seam of two layers, forming three layers with the adjacent part of the sleeve, and the shoulder 26 is at or in this bent-down seam. In Figure 19 I have shown the cathode sleeve 20 of Figure 18 assembled with a grid 78 and anode 79, in a manner somewhat similar to the arrangement shown in Figure 4 of Patent 2,079,057. In Figure 19 the numeral 80 designates an upper mica disk and 81 designates a lower mica disk, supported by posts 82. The sleeve 20 contains 75 the usual resistance element or heater including

lead-in wires 83 and the sleeve is coated at 84 with barium or strontium carbonate, corresponding to the coating 17 of Patent 2,079,057. This coating when raised to the proper temperature becomes a good emitter of electrons. The tab 22^a formed by the tab sections 23 and 24 may be bent slightly so that it can be attached or welded to one of the posts 49. The shoulder 26 rests upon the top of the disk 81, and supports the sleeve, the ends of which are inserted within openings 85. 10 5

It is to be understood that the form of my invention herewith shown and described is to be taken as a preferred example of the same and that various changes in the shape, size, and arrangement of parts may be resorted to without departing from the spirit of my invention or the scope of the subjoined claims. 15

Having thus described my invention, what I claim is:

1. The method of producing a cathode sleeve 20 for a thermionic valve, comprising stamping an opening in one end of a metal strip to provide longitudinally extending tab sections formed integral with the strip near its longitudinal edges, bending the strip carrying the tab sections about 25 its longitudinal axis, applying pressure to the outer sides of the strip near its longitudinal edges to complete the bending for forming a sleeve having laterally and outwardly extending flanges with the tab sections constituting continuations of the flanges, each flange and each tab section consisting of a single layer, and welding the flanges together and the tab sections together while maintaining each flange and each tab section 30 in the single-layer condition. 35

2. The method of producing a cathode sleeve for a thermionic valve, comprising forming longitudinally extending single-layer tab sections integral with and upon one end of a strip of sheet metal adjacent to the longitudinal edges of the 40 strip, bending the strip about its longitudinal axis to produce the sleeve and forming longitudinal single-layer flanges at the side edges of the sleeve, the tab sections constituting extensions of the flanges, and welding the flanges together and the 45 tab sections together while maintaining each flange and each tab section in the single-layer condition. 50

3. The method of producing a cathode sleeve for a thermionic valve, comprising forming an 50 opening in a metallic sheet for providing a body portion and spaced single-layer tab sections extending longitudinally beyond one end of the body portion, bending the body portion about its longitudinal axis for forming a sleeve and single-layer longitudinal flanges projecting laterally of the sleeve, and welding the flanges together and the tab sections together while maintaining each flange and each tab section in the single-layer condition. 55

4. The method of producing a cathode sleeve for a thermionic valve, comprising forming an opening in a metallic sheet to provide a body portion and spaced single-layer tab sections adjacent to the longitudinal edges of the body portion and 65 extending beyond the end of the body portion, bending the body portion about its longitudinal axis for forming a sleeve and single-layer longitudinal flanges projecting laterally beyond the outer surface of the sleeve while causing the tab 70 sections to substantially align with the flanges, bringing the flanges in opposed substantially parallel close relation while bringing the tab sections in opposed substantially parallel close relation, and welding the flanges together and the 75

- tab sections together while maintaining each flange and each tab section in the single-layer condition.
5. The method of producing a cathode sleeve for a thermionic valve, comprising forming an opening in a metallic sheet to provide a body portion having longitudinal edges and longitudinally extending spaced single-layer tab sections adjacent to the longitudinal edges, bending the body portion about its longitudinal axis for forming a sleeve and single-layer longitudinal flanges projecting laterally upon the outer side of the sleeve, bringing the flanges in opposed close relation and bringing the tab sections in opposed close relation, and welding the flanges together and welding the tab sections together while maintaining each flange and each tab section in the single-layer condition.
6. The method of producing a cathode sleeve for a thermionic valve, comprising forming an opening in a metallic sheet to provide a body portion and spaced single-layer tab sections extending beyond the end of the body portion, bending the body portion about its longitudinal axis for forming a sleeve and single-layer longitudinal flanges projecting laterally upon the outer surface of the sleeve, arranging the flanges in overlapping relation and welding them together and arranging the tab sections in overlapping relation and welding them together while maintaining each flange and each tab section in the single-layer condition, and bending down a portion of the welded together flanges to lie in close relation upon the outer surface of the sleeve.
7. The method of producing a cathode sleeve for a thermionic valve, comprising forming an opening in a metallic sheet to provide a body portion and spaced single-layer tab sections extending beyond one end of the body portion, bending the body portion about its longitudinal axis for forming a sleeve and single-layer longitudinal flanges projecting laterally upon the outer surface of the sleeve, arranging the flanges in overlapping relation and the tab sections in overlapping relation, welding the flanges together and the tab sections together, bending down a portion of the welded flanges upon the outer surface of the sleeve, and forming a stop shoulder upon the flanges.
8. The method of producing a cathode sleeve for a thermionic valve, comprising stamping an opening in one end of a metal strip to provide longitudinally extending tab sections formed integral with the strip near its longitudinal edges, forming raised portions along one longitudinal edge and one tab section, bending the strip carrying the tab sections about its longitudinal axis and applying pressure in an inward direction to the strip adjacent to its longitudinal edges and the tab sections for forming a sleeve having outwardly extending flanges, each flange and each tab section consisting of a single layer, and welding the flanges together and the tab sections together while maintaining each flange and each tab section in the single-layer condition.
9. The method of producing a cathode sleeve for a thermionic valve, comprising forming longitudinally extending tab sections integral with and upon one end of a sheet metal strip adjacent to the longitudinal edges of the strip, forming a group of raised portions upon the strip which group extends longitudinally of one longitudinal edge and one tab section, bending the strip about its longitudinal axis to produce the sleeve and forming longitudinal single-layer flanges, and welding the flanges together and the tab sections together while maintaining each flange and each tab section in the single-layer condition.
10. The method of producing a cathode sleeve for a thermionic valve, comprising forming a group of raised portions adjacent to and extending longitudinally of one longitudinal edge of an elongated strip, stamping an opening in one end of the strip to provide single-layer tab sections with the raised portions upon one tab section, bending the strip about its longitudinal axis into a sleeve having single-layer flanges at the longitudinal edges, and bringing the flanges and tab sections into close relation and welding the same together while maintaining the tab sections and the flanges in the single-layer condition and securing them together solely by the welding.
11. The method of producing a cathode sleeve for a thermionic valve, comprising bending a flat elongated metallic strip into a V-shape and forming a group of raised portions adjacent to one longitudinal edge of the strip and extending longitudinally of the edge, forming an opening in one end of the strip to provide longitudinal single-layer tab sections with the raised portions extending longitudinally upon one tab section, bending the V-shaped strip about its longitudinal axis to form a sleeve to provide overlapping single-layer portions and for causing the tab sections to overlap, and welding the overlapping portions and the overlapping tab sections together while maintaining the tab sections and the overlapping portions in the single-layer position and securing them together solely by the welding.
12. The method of producing a cathode sleeve for a thermionic valve, comprising forming an opening in a metal strip to provide longitudinally extending single-layer tab sections formed integral with the strip near its longitudinal edges, bending the strip about its longitudinal axis for forming a sleeve and generally radial outwardly extending single-layer flanges and inclining the flanges, welding the flanges together and the tab sections together while maintaining the flanges and tab sections in the single-layer condition and thereby securing the same together solely by the welding, and applying pressure to the inclined flanges in a direction toward the sleeve to bend down the inclined flanges.
13. The method of producing a cathode sleeve for a thermionic valve, comprising forming single layer tab sections integral with a metal strip adjacent to the longitudinal edges of the metal strip, bending the strip about its longitudinal axis to produce the sleeve and forming longitudinal single-layer flanges at the side edges of the sleeve, the tab sections extending beyond the sleeve from points adjacent to the flanges, and welding the flanges together and the tab sections together while maintaining each flange and each tab section in the single-layer condition.
